UNITED STATES PATENT OFFICE.

CHARLES S. BUSHELL AND FRED W. DEGLER, OF MENASHA, WISCONSIN.

SUPPORT FOR WASHTUBS.

SPECIFICATION forming part of Letters Patent No. 516,260, dated March 13, 1894.

Application filed February 13, 1893. Serial No. 462,036. (No model.)

To all whom it may concern:

Be it known that we, CHARLES S. BUSHELL and FRED W. DEGLER, citizens of the United States, and residents of Menasha, in the county 5 of Winnebago and State of Wisconsin, have invented a new and useful Improvement in Supports for Washtubs, of which the following is a specification.

Our invention relates to a support for wash 10 tubs, or a leg for clamping upon the sides of a tub at three points in its circumference for the purpose of holding the tub in a sufficiently elevated position for the convenience of the person using it, and the object of our invention 15 is, to provide a device for holding tubs which is of low cost, is of light weight, is convenient for use, and can be stored away in a small space. We attain these objects by means of the construction shown in the accompanying drawings, in which—

Figure 1 is an elevation, showing a wash tub, elevated and resting upon three supports of our invention. Fig. 2 is a plan, showing a top view of a tub thus supported. The nine 25 following figures are upon a larger scale than Figs. 1 and 2. Fig. 3 is a side elevation of one of the tub supports. Fig. 4 is an edge view of said support. Fig. 5 is a side view of a support having a modification in the de- 30 vices for securing the support upon a tub, the upper part being in section on line *a*, *a*, Fig. 6, and Fig. 6 an edge view of the support having said modification thereon. The following figures are details, Fig. 7 being a rear, or an 35 outside view of the hook in Figs. 1, 2, 3 and 4, which is secured to the leg, or wood part of the support, for clasping over the top edge of the tub; Fig. 8 a side view of said hook; Fig. 9 a top view thereof; Fig. 10 a top view of a 40 bracket which is used in the modification, (Figs. 5 and 6,) for supporting the chine of the tub upon; Fig. 11 a side view of said bracket; Fig. 12 a side elevation of a hook which is used in the modification, (Figs. 5 and 45 6,) for application to the upper end of the leg and for clasping over the upper edge of the tub; Fig. 13 a top view of said hook; Fig. 14 a view of the rear, or outer side of said hook, and Fig. 15, an elevation of a plug and spring 50 guide which are used with the hook modification. Figs. 12, 13, 14 and 15, are upon a larger scale than the nine preceding figures.

Similar figures of reference indicate like parts in the several views.

1 indicates an ordinary wash tub; 2, 2', the supports, or legs of our invention; 3, 3', the tub supporting brackets; 3", 3'", holes in the brackets 3' for receiving a pin or bolt; 4, links which connect the bracket 3 and leg 2; 4', pins, or rivets for connecting the link to the bracket 60 and leg; 5, an eccentric lever; 5', a bolt for connecting said lever and the leg 2; 6, a slot in the leg near its upper end; 6', a pin through the leg and said slot; 7, a hook for engaging with the upper edge of the tub and holding 65 the tub between said hook and the bracket 3; 7', a guiding rib on said hook; 7", notches in said rib; 7", an arm extending downward from said rib; 7", ears upon the outer end of said arm; 8, a spring hook for engaging 70 with the upper edge of the tub in the modification, (Figs. 5, 6, 12, 13 and 14); 8', a lug on the hook 8; 8", a hole in said lug; 8", a band integral with the hook 8 and extending around the upper end of the leg 2'; 9, a circular hole 75 in the upper end of the leg 2', for receiving the lug 8'; 10, a plug and spring guide; 10', a pin for securing said plug to the leg 2'; 10", a coiled spring; 11, a slot in the leg for receiving the bracket, 3'; 12, holes through 80 the leg 2', for receiving the bolts upon which to adjust the bracket upon the leg at different heights; 12', 12", bolts for the bracket 3'; 13, a slot in the legs 2 and 2', for receiving an extension piece; 13', a pin in the leg and 85 through said slot for adjusting the extension piece vertically; 14, a leg extension piece; 14', a rib thereon; 14", notches in said rib; 14", an arm extending upward from said rib; 14", ears on the outer end of said arm; 15, 90 a lug upon the extension piece; 16, a spring connected to said lug.

Referring to the supporting legs shown upon the tub, we make them and also, the brackets 3 and eccentric lever, for the purpose of securing lightness, preferably of wood of a good quality, the bracket and eccentric may however be made of metal if it is found to be desirable. The legs are prepared of the desired form and provided with the slot 6, a pin 6', hook 7, eccentric lever 5, bolt 5', bracket 3, links 4 and rivets 4', which parts when properly assembled constitute one of the supporting legs. Three of these legs comprise

one set which are applied at the several points around the tub as shown in Fig. 2. The legs are adjusted to fit the height of the tub by placing the proper notch, 7", upon the 5 pin 6', for giving the necessary distance for taking in the tub between the bracket 3 and the upper end of the hook. The hook is then hooked over the top of the tub and the bracket brought under the chine, when with a partial 10 turn of the eccentric lever the bracket is forced upward against the chine of the tub and the leg thereby secured firmly. The tub in Fig. 1 has a part of its top and bottom broken away and showing the hook 7 and bracket 3 upon the center leg clamped over the top and bottom edges of the side of the tub. The bracket 3 is connected loosely with the leg by means of the links 4 and pins or rivets 4', whereby it can be raised upon the leg by the 15 turning of the eccentric lever. It will be observed that the ears 7", upon the hook 7, are arranged in position below the lower end of the body of the hook and at a distance from said body, for the purpose of allowing the top of 20 the hook to be thrown away from the leg for disconnecting the notches 7" from the pin 6', as it is shown to be by the dotted outline of the hook in Fig. 3. After the three legs are applied, which is best done with the tub resting 25 upon its side, the tub is placed in position for its use, as shown in Fig. 1. When it is desired to remove the legs the tub should be turned upon its side and a turn given to the eccentric lever of each leg, when the several 30 legs may be taken off and hung up, or laid away in any convenient place. They occupy but little room, and being designed especially for supporting wash tubs, will not be likely to be used for any other purpose, but be always 35 ready for use.

In the modification of the leg, Figs. 5 and 6, a different way of constructing the tub connecting device is provided. The legs 2' are provided intermediate their ends with a slot 45 11 for receiving the bracket 3', and in their top with a circular hole 9, which hole communicates with the inside of the leg and is adapted to receive the circular ended lug 8', of the hook 8. In the upper end of Fig. 5 the 50 leg 2' and hook 8 are shown in section upon the line a, a, of Fig. 6, the more plainly to show the construction of the parts. The bracket 3', is provided with holes 3" and 3", for receiving a pin, or bolt, 12' and 12", the former 55 of which bolts is adapted to enter any one of the holes 12 for the purpose of adjusting the bracket at different heights upon the leg for meeting the requirements of tubs of different lengths, and the latter bolt is for insertion 60 into the hole 3", for bearing against the leg and preventing the bracket from turning and allowing the tub to drop from it. The hook 8 is provided with the circular ended lug, 8' and band 8", the lug being adapted to enter 65 and to move vertically in the hole 9, and the band to surround the upper end of the leg, 2', and to permit the hook to move easily up and

down upon it. A plug 10, is provided for entering and closing the upper end of the hole 9, said plug having a wire extended centrally 70 from its lower end which is adapted to pass easily through a hole, 8", in the lug 8', and is of sufficient length to extend into the leg below the bottom of the hole 9. The plug is provided with a hole for receiving a pin 10' for connecting the plug to the leg. The hook 8 being placed in its position upon the leg, a spring, 10", which may be made of wire wound into a cylindrical form, is provided and placed upon the lug 8', when the plug may be inserted and secured 80 to the leg, its wire passing downward inside of the spring, through the lug 8' and into the wood of the leg, and serving thereby as a guide for the spring and for holding the lower end of the hook 8 upon the leg. By taking 85 hold of the upper extremity of the hook it can be raised, relative to the leg, an amount within the limit of the compression of the spring, 10", and the hook brought over the upper edge of the tub, when the hold upon the hook 90 being released, the spring thereof will expand and force the hook down upon the tub and thereby secure the leg upon the tub. The leg can be quickly and easily removed by taking hold of the upper end of the hook, giving to 95 it a slight pull, and compressing the spring sufficiently for allowing the hook to be released from the edge of the tub.

Sets of the legs, 2 or 2', may be made of different lengths from their lower ends to the tub 100 supporting brackets, for the purpose of adapting them for the use of persons of different heights, but for the purpose of adapting one set for the use of both, a tall or a short person, we provide a leg extension piece, 14. 105 For the application of the extension pieces the legs are each provided with a slot, 13, shown in Fig. 1, extending from the lower end of the leg upward a short distance, and the legs are also provided with a pin, 13', near 110 their lower ends. The extension piece 14, has upon its outer side a rib 14', having numerous notches 14", any one of which is adapted to be hooked upon the aforesaid pin. Said extension piece has also upon its outer 115 side an arm 14", extending upward from the rib 14', and is provided upon its outer extremity with ears 14", which ears like the ears 7", upon the hook 7, are located relative to the body of the piece, for allowing said 120 piece to be thrown away from the leg for allowing the connection and disconnection of the notches 14" from the pin 13'. Upon one side of the extension piece is a lug 15, into which two small holes are drilled for receiving the wire spring 16. One of said holes is drilled only partly through the lug into which one end of the spring is inserted, and the other hole drilled entirely through and the wire of the spring passed through it and bent 125 around at a right angle and against the lug, whereby the spring is held from longitudinal movement. The spring is bent so as to have its upper, or free end, bear against the leg 130

above the extension piece, and when the pin 13' engages one of the notches 14", hold said piece against the leg.

When it is desired to change the position 5 of the extension piece upon the leg for raising or lowering the height of the tub, it is only necessary to take hold of it by its lower end, disconnect the notch then engaging the pin 13', slide said piece up, or down, and engage some other notch, the spring 16, while 10 allowing said movement, when the leg is supporting the tub, keeps the extension piece in close contact with the leg.

Having described our invention, what we 15 claim, and desire to secure by Letters Patent, is—

1. A leg for supporting a wash tub in an elevated position, having a slot extending from its upper end downward, a pin transversely through said leg and slot, a hook arranged upon the leg for grasping over the upper edge of the tub, said hook extending downward upon the leg and being provided with a rib having a series of notches therein, 25 the rib being adapted for a longitudinal movement in said slot, and the notches for engagement with said pin, and means for retaining the hook upon the leg while allowing the disengagement of said notches from the pin 30 aforesaid, substantially as described.

2. A wash tub support, consisting of a leg having a slot extending from its top end downward, a pin through the leg and slot, transversely of the slot, a hook adapted to engage the tub by its upper edge, said hook being provided with a projecting rib adapted for movement longitudinally of the slot, notches 35

in said rib arranged for engagement and disengagement with the pin aforesaid, said rib having also an arm extending through the 40 slot having ears thereon adapted to hold the hook upon the leg, and also, to permit said engagement and disengagement of the notches and pin aforesaid, a tub supporting bracket hinged upon the leg, and an eccentric lever 45 arranged for raising said bracket, and for clamping the tub between the bracket and hook aforesaid, substantially as described.

3. In a leg for supporting a wash tub in an elevated position, a leg extension piece, 14, a 50 slot in the leg from its lower end upward adapted to receive said extension piece, and a pin transversely through said slot and leg, said extension piece having a rib, 14', notches, 14", ear, 14'", lug, 15, and spring, 16, substantially as set forth.

4. A leg for supporting a wash tub in an elevated position, having in combination, a mechanism for securing said leg to the side of the tub, consisting of a hook for engaging 60 the top of said side and a bracket arranged for supporting its bottom, said mechanism being provided with means for its compression upon the ends of said side, and thereby to clamp the leg upon the tub, and both the 65 hook and bracket being adjustable upon the leg for adapting the leg to tubs of different lengths of sides, substantially as described.
